UNITED STATES PATENT OFFICE.

JOSEPH LONGINOTTE, OF CINCINNATI, OHIO.

CAR-COUPLING.

SPECIFICATION forming part of Letters Patent No. 730,038, dated June 2, 1903.

Application filed March 14, 1903. Serial No. 147,755. (No model.)

To all whom it may concern:

Be it known that I, JOSEPH LONGINOTTE, a citizen of the United States, residing at Cincinnati, in the county of Hamilton and State of Ohio, have invented a new and useful Improvement in Car-Couplers, of which the following is a specification.

My invention relates to an improvement in car-couplings, and more particularly to means for opening the knuckle after it has been unlocked by the locking device.

The object of my invention is to provide a simple and certain means, adaptable to many of the commonly-termed "twin-jaw" couplers, for throwing the knuckle open when the latter is unlocked by the locking pin or device, and thus obviate the necessity of a man entering between the cars to open the knuckle by hand. I am aware that there have been many attempts to accomplish this object, some using a spring adapted to act directly or through intermediate members upon the knuckle; but springs are not positive. Others have arranged the locking device so that the force of gravity can cause it to throw open the knuckle; but this also is not positive. Still others have used a cam-surface on the locking device for this purpose, and while this gives a positive means for throwing the knuckle open it also makes the locking-pin work hard. My invention has the advantages of a cam for insuring the certain opening of a knuckle; but it does not work as hard because of a spring which I have devised to assist the cam or inclined surface, the said spring having been compressed when the coupling took place, and it can be strong enough to open the knuckle with little or no help of the cam, the latter only making the action of the former certain, as the spring alone might fail to open the knuckle because of rusting after long standing or because it had become weak through much use.

Referring to the drawings, which form a part of this specification, Figure 1 is a sectional view of Fig. 2 on the line X X, showing the knuckle 3 in its closed position pivotally mounted upon the pin 8 and my improved opening-lever 4 pivotally mounted on the pin 6 and having a cavity 4" containing a spiral spring 5, mounted upon the pin 6. The ends of the spring are held in compression

between the side of the cavity 4" and the coupler-head 1, thus causing the end 4'" of the lever 4 to press on the knuckle 3 in the direction of the arrow. The lever 4 has a tail 4', the under part of which, 4'"', is beveled, shown more clearly in Fig. 2, which is a partial sectional view of Fig. 1 on the line Y Y. This inclined surface is adapted to coact with an inclined surface 7'" on the lug 7", forming a part of or attached to the locking pin or device 7, as will now be explained, together with the whole action of my improved knuckle-opener. The knuckle being closed, as shown in Figs. 1 and 2, it is unlocked and opened as follows: The locking-pin 7 is raised by any of the usual means until the edge of the inclined portion 7' is above the tail 3' of the knuckle, when the spring 5, through the lever 4, will very nearly or altogether push the knuckle into the open position dotted in Fig. 1; but to assist and make certain the action of the spring the locking-pin is further raised to its highest position, (shown by the dotted lines 7' in Fig. 2,) bringing the inclined surface 7'" on the locking-pin into operative contact with the inclined surface 4'" on the tail 4' of the lever 4 and forcing the lever into the dotted position shown in Fig. 1, thus making the opening of the knuckle certain when the locking-pin is wholly raised.

I do not confine my invention to this particular construction, for it is clear that the lug 7" and inclined surface 7'" could be deformed on almost any knuckle-unlocking device and the coupler-head arranged to contain my knuckle-opening lever, having an inclined surface 4'".

Having thus described my invention, I claim as new and desire to secure by Letters Patent—

1. In a car-coupling, the combination with a coupler-head, of a knuckle pivoted therein, a knuckle-unlocking device having a cam-surface adapted to coact with a cam-surface on a spring-actuated member, to insure the certain opening of the knuckle, substantially as described.

2. In a car-coupling, the combination with a coupler-head, of a knuckle pivoted therein, a locking-pin having an inclined surface adapted to coact with an inclined surface on a spring-actuated lever, to insure the certain

opening of the knuckle, substantially as described.

3. In a car-coupling, the combination with a coupler-head, of a knuckle pivoted therein, 5 and adapted when moved into its coupled position to be locked by a locking device, and also to move a spring-actuated member having an inclined surface, into a position to be actuated by an inclined surface on the un-locking device, substantially as and for the 10 purposes specified.

4. In a car-coupling, the combination with a coupler-head, of a knuckle pivoted therein,

a locking-pin having an inclined surface, adapted to coact with an inclined surface on 15 a spring-actuated lever, the spring being located in a cavity in the lever and on the fulcrum thereof substantially as and for the purposes specified.

In testimony whereof I have signed my 20 name to this specification in the presence of two subscribing witnesses.

JOSEPH LONGINOTTE.
